UNITED STATES PATENT OFFICE.

JOHN W. OLDHAM, OF WANETTE, OKLAHOMA, ASSIGNOR OF ONE-HALF TO SAMUEL J. WEAVER, OF WANETTE, OKLAHOMA.

PACKAGE-TIE.

1,200,012.

Specification of Letters Patent.

Patented Oct. 3, 1916.

Application filed November 26, 1915. Serial No. 63,474.

To all whom it may concern:

Be it known that I, JOHN W. OLDHAM, citizen of the United States, residing at Wanette, in the county of Pottawatomie and

5 State of Oklahoma, have invented new and useful Improvements in Package-Ties, of which the following is a specification.

The device which is the subject-matter of the present application for patent is de- 10 signed more particularly for tying packages of letters and other mail matter, although it is not limited to such use, but may be employed for tying any other packages.

The object of the invention is to provide 15 a device of the kind stated which is simple in construction, which can be easily and quickly applied, and which will securely hold the package or bundle of letters or other articles.

20 With the object stated in view, the invention consists in a novel combination and arrangement of parts to be hereinafter described and claimed, reference being had to the accompanying drawing in which—

25 Figure 1 is a perspective view showing the application of the invention; Fig. 2 is a central longitudinal section of a device for securing the ends of the cord whereby the package is tied; Fig. 3 is a longitudinal 30 section of said device in a plane at right angles to the preceding view, and Fig. 4 is a side elevation of the device, partly in section, showing the spring latch.

Referring specifically to the drawing, 5 35 denotes the package to which the tie device is applied, said device comprising a cord, band or similar member 6 which is passed around the package in two directions. A device is provided for enabling the cord 40 to be passed around the package in this manner and tightened up, and a fastener is applied to the ends of the cord for holding the same tightly drawn around the package.

45 The device for holding the cord 6 around the package 5 comprises a clip consisting of a small metallic plate 7 having its ends rolled into guide eyes 8. The clips are dia- 50 ginally and centrally positioned, and the cord passes through the eyes 8 from one clip to the other in such a manner that it

is carried around the package in two directions. The cord passes loosely through the eyes 8 so that it may be tightened by a pull on its ends.

The device for securing the ends of the cord 6 comprises a cylindrical member 9 having two external, diametrically opposite grooves 10 in which the respective ends of the cord 6 are adapted to be placed. On 60 the member 9 is slidably mounted, in the direction of the length thereof, a sleeve 11. It will be noted that the grooves taper or gradually decrease in depth and width to- 65 ward one end thereof to produce a wedging action on the cord. The two ends of the cord are securely clamped and held in the grooves upon sliding the sleeve in the di- 70 rection of the smaller ends of the groove, and upon sliding the sleeve in the oppo- 75 site direction, the cord ends are released. Before tightening the cord around the pack- 80 age, the ends of the cord will be released as described, and after tightening up the cord around the package, the sleeve is advanced 75 to bind the said ends in the grooves 10 as described.

The sleeve 11 is locked in clamping position by a spring latch 12 carried by the member 9 and seating in a longitudinal slot 85 13 in the sleeve. Before the sleeve can be retracted to release the cord ends, the latch must be depressed sufficiently to clear the sleeve, the member 9, opposite the latch hav- 90 ing a recess 14 to enable the latch to be de- pressed sufficiently to clear the sleeve. The member 9 also carries diametrically oppo- 95 site, outstanding pins 15 seating in longi- tudinal slots 16 in the sleeve 11, whereby relative rotary movement of the member 90 and the sleeve is prevented.

The end of the member 9, at the smaller ends of the grooves 10, carries an eye 17 through which the cord 6 is passed before entering the grooves 10, the cord being 95 crossed in the eye, so that when the two ends of the cord are given a pull the cord will be tightly drawn around the package.

It will be seen from the foregoing that the device can be easily and quickly applied 100 to the package and adjusted to tie the same, and it can also be readily removed so that

it may be used again on other packages.

I claim:

A cord fastener comprising a member having external longitudinal grooves in which the cord ends are adapted to seat, said grooves tapering toward one end, a sleeve mounted on the member adapted to slide in

the direction of the length thereof for wedging the cord ends in the smaller ends of the grooves, and means for locking the sleeve on the member.

In testimony whereof I affix my signature.

JOHN W. OLDHAM.
